SWITCH THROW STAND

Filed June 29, 1929

FIG. 1.

FIG. 3.

FIG. 2.

FIG. 4.

UNITED STATES PATENT OFFICE

JOHN O. GILL, OF BARNESBORO, PENNSYLVANIA

SWITCH-THROW STAND

Application filed June 29, 1929. Serial No. 374,699.

This invention relates to a switch throw stand, and has for one of its objects to provide a novel and highly efficient device of this character which shall be adapted to be used 5 in connection with an underground or surface track switch of any type.

The invention has for a further object to provide a switch throw stand which shall be adapted to prevent the switch from occupying 10 a partly opened or partly closed position and shall be adapted when actuated to positively throw the switch from its fully opened to its fully closed or from its fully closed to its fully opened position.

15 The invention has for a further object to provide a switch throw stand which shall be so constructed as to render it impossible for the operator to be injured thereby and to require the minimum clearance for the installation and operation thereof.

20 The invention has for a further object to provide a switch stand which shall be adapted to be easily and quickly adjusted so as to increase or decrease the length of the throw 25 of the rod connecting it to the switch.

25 The invention has for a still further object to provide a switch stand which shall be rigid, durable, simple and light in weight without sacrificing strength and wearing qualities, 30 and which shall be capable of being manufactured and sold at a comparatively low cost.

With the foregoing and other objects in view, the nature of which will appear as the 35 description proceeds, the invention consists in the construction, combination and arrangement of parts hereinafter fully described and claimed and illustrated in the accompanying drawings, wherein:—

40 Figure 1 is a view in front elevation of the switch throw stand;

Figure 2 is a view in side elevation of the switch throw stand;

45 Figure 3 is a view in side elevation of the lower portion of a slightly modified form of the switch throw stand; and

Figure 4 is a detailed sectional view taken on the vertical plane indicated by the line 4—4 of Figure 3.

50 The switch throw stand comprises a base 1

which embodies a horizontal portion or flange 2 and a vertical portion or flange 3. The base 1 is adapted to be secured to a tie 4 through the medium of its flange 2, such flange resting upon the tie and adapted to be secured thereto in any suitable manner. The flange 3 extends upwardly from the longitudinal edge of the flange 2, and said flanges are substantially of the same length. An upright or standard 5 is secured to the base 1 at the 55 transverse center of the latter. The standard 5 has its lower end resting upon the flange 2 and has its lower end portion contacting with the rear side of the flange 3. A brace 6 of inverted V-form is secured at its ends to the 60 base 1, and is offset at its apex to provide a socket 7 for the reception of the standard 5.

The ends of the brace 6 rest upon the flange 2 and their end portions contact with the rear side of the flange 3, and the socket 7 contacts 65 with the rear and lateral sides of the standard 5. The base 1, standard 5 and brace 6 may be welded to each other or secured in assembled relation by rivets 8.

A lever 9 is pivotally connected at one 70 side of its transverse center to the standard 5 through the medium of a bolt 10, and the bolt is engaged with the standard at a point between the base flange 3 and the brace socket 7. The lever 9 is arranged at the 75 front side of the standard 5, and is spaced therefrom by a collar 11 which is mounted upon the bolt 10 between the lever and standard. The lower or shorter arm 9^a of the lever 9 is offset to space it forwardly beyond the base flange 3, and secured at the 80 lower end of this arm is a rod 12 which is connected to the switch. The rod 12 is provided with a clevis 13 which embraces the lower end of the lever arm 9^a and is connected thereto by a bolt 14. The upper or longer arm 9^b of the lever 9 is provided at its upper 85 end with a sliding block 15 which is provided with a bore 16 and a pivot lug 17. The bore 16 and pivot lug 17 are right angularly related, and the latter is rotatably arranged in an opening 18 in the upper end of the lever arm 9^b. The block 15 is arranged at the front 90 side of the lever 9 and a cotter pin 19 or other suitable element, carried by the pivot lug 17 100

and contacting with the rear side of the lever, maintains the pivotal connection between the block and lever. A turning block 20 is pivotally connected to the upper end of the standard 5, and it is provided with a bore 21 and a pivot lug 22 which are right angularly related.

The block 20 is arranged at the front side of the standard 5, and the lug 22 thereof passes through an opening 23 in the standard. A cotter pin 24 passing through the pivot lug 22 and contacting with a washer 25, mounted upon the pivot lug between the standard 5 and cotter pin, maintains the pivotal connection between the block 20 and the standard.

A handle 26 passes through the sliding block 15 and the turning block 20, and has its upper end reduced and formed to provide a grip 27. The handle 26 has a fixed position with respect to the turning block 20 and a slidable connection with the sliding block 15, and it is fixed to the turning block by a set screw 28 or the like. The sliding block 15 is held against displacement from the handle 26 by a pin 29 which passes through the handle and upon which rests the block. A coil spring 30 is mounted upon the handle 26 between the sliding block 15 and the turning block 20 and bears at its ends against the blocks.

When the switch throw stand is in use, the lever 9 and handle 26 are angularly related to each other and the standard 5 when the switch is in either closed or opened position, and the lever and handle are held in their angular relation, and the switch is held in closed or opened position, by the spring 30. When the switch is closed, the lever 9 and handle 26 occupy the position in which they are shown by solid lines in Figure 1, and when the switch is opened, the lever and handle occupy the position in which they are shown by broken lines in said figure. It will thus be apparent that by throwing the lever 9 from its solid line to its broken line position, the switch will be opened, and that by throwing the lever from its broken line to its solid line position, the switch will be closed, the lever being thrown by the handle 26.

During the movement of the lever 9 from one of its positions to the other, the spring is compressed, and the spring is under the greatest compression when the lever and handle are in vertical alinement, with the result that when the lever is moved to one side or the other of the vertical, the spring will react and positively move the switch from one of its positions to the other. The switch cannot have any intermediate position due to the fact that the spring 30 begins to react immediately after the lever 9 has been moved beyond the vertical. To adjust the throw or distance of travel of the lower end of the lever 9, it is only necessary to adjust the sliding block 15 upwardly upon the handle 26 when

it is desired to decrease the throw and downwardly when it is desired to increase the throw. The sliding block 15 is held in its adjusted position through the medium of the pin 29 which is arranged in a selected opening of a series 29^a in the handle 26.

The switch throw stand described is adapted for light duty, and to convert it into a heavy duty stand, it is only necessary to increase the number of levers to two, as shown in Figure 3. The levers 31 are connected to the standard 5 by a bolt 32. They are held in relatively spaced relation by a collar 33 carried by the bolt 32, and they are held in spaced relation to the standard 5 by a collar 34 also carried by the bolt. In this form of the invention, the sliding block 15^a is provided with two pivot lugs 22 with which the upper ends of the levers 31 are engaged, and the levers are provided at their lower ends with a block 35 which is arranged between said ends of the levers and connected thereto by pivot lugs 36.

The block 35 is provided with a passage for the reception of a threaded end 37 of a switch rod 38, and these parts are connected together by nuts 39 carried by the rod and engaging opposite sides of the block. The other parts of the switch throw stand shown in this figure are similar to the corresponding parts of the device shown in Figures 1 and 2 and are designated by the same reference characters. In both forms of the invention, the bores through the blocks are spaced from the lever and stand sufficiently to prevent the spring from contacting with said parts and thus insure the free contraction and expansion of the spring during the movement of said parts.

While I have described the principle of the invention together with the structure which I now consider the preferred embodiment thereof, it is to be understood that the structure shown is merely illustrative and that such changes may be made, when desired, as fall within the scope of the invention as claimed.

I claim:—

1. A switch throw stand comprising a support, a lever pivoted intermediate its ends to the support and adapted to have its lower end connected to a switch, a handle, means pivotally connecting an intermediate portion of the handle to the support, means pivotally and slidably connecting the lower end of the handle to the lever, and a coil spring surrounding the handle between and bearing at its ends against said means and normally tending to hold the handle and lever in angular relation, said means spacing the handle and spring from said support and lever so as to permit the free compression and expansion of the spring during the movement of the handle and lever.

2. A switch throw stand comprising a sup-

port, a lever pivoted intermediate its ends to the support and adapted to have its lower end connected to a switch, a block pivotally connected to the upper end of the lever and provided with a bore, a block pivotally connected to the support above the path of movement of said first block and provided with a bore, a handle passing through the bores of the blocks, means securing an intermediate portion of the handle to said second block, the lower end of the handle and said first block being slidable with respect to each other, means for limiting the downward movement of said first block with respect to the handle, and a coil spring surrounding the handle between and bearing at its ends against the blocks and tending to normally hold the handle and lever in angular relation, the bores of the blocks being spaced from the support and lever sufficiently to prevent the spring from contacting with said parts and thus permit the free contraction and expansion of the spring during the movement of said parts.

25 In testimony whereof I hereunto affix my signature.

JOHN O. GILL.
